UNITED STATES PATENT OFFICE.

WINFIELD S. HAYS, OF HOUSTON, TEXAS.

AUTOMOBILE SAFETY SWITCH.

Application filed May 20, 1922. Serial No. 562,464.

To all whom it may concern:

Be it known that I, WINFIELD S. HAYS, citizen of the United States, residing at Houston, in the county of Harris and State 5 of Texas, have invented certain new and useful Improvements in an Automobile Safety Switch, of which the following is a specification.

This invention relates to new and useful 10 improvements in an automobile safety switch.

One object of the invention is to provide a switch of the character described whereby the magneto and battery may be cut into or 15 out of the circuit and is provided as a guard against short circuits in the electric system and will prevent the generator from burning out, and the battery from running down due to faulty cut out switch.

20 Another object of the invention is to provide a safety switch whereby danger from fire will be eliminated by reason of short circuit and which will prevent the vehicle from being started and the horn and lights 25 from being used by meddlers. The switch is therefore a protection against theft, and when the switch is locked open the car can not be used.

A still further feature of the invention 30 resides in the provision of a safety switch which is of simple construction and may be cheaply and easily manufactured and applied to any make of automobile.

With the above and other objects in view 35 the invention has particular relation to certain novel features of construction, operation and arrangement of parts, an example of which is given in this specification and illustrated in the accompanying drawings, 40 wherein:—

Figure 1 is a plan view of the device with the switch plug removed.

Figure 2 is a sectional view thereof showing said plug inserted.

45 Figure 3 is a bottom view.

Figure 4 is a fragmentary sectional view showing an electrical contact tongue employed.

Figure 5 is a side view of the switch plug.

50 Figure 6 is an enlarged fragmentary sectional view of the device and,

Figure 7 shows a plan view of the metallic plate embodied in the switch.

Referring now more particularly to the drawings, the switch block is preferably 55 composed of three plates 1, 2 and 3, the latter of which is metal and the two former of which are formed of rubber or other insulating material. These plates are clamped together by means of the bolts 4, 4, 60 each of which has a surrounding tubular insulator 5, and clamped against the outer face of the metallic plate 3 there are thin plate like insulators 6 and 7 which are also held in place by the bolts 4, 4. The switch block has a central socket 8 to receive the switch plug 9. This plug is formed of hard rubber or other insulating material and its inner end is surrounded by a metal collar 10 which is shrunk thereon and the plug is 70 also formed with annular grooves 11 and 12 therearound. There are two binding posts 13, 13 which are threaded into the plate 3 and the terminals of the wiring 14, leading to the battery are connected to these binding 75 posts. It is to be noted that the plate 3 is formed of two sections spaced apart, as illustrated in Figure 7, and one of the binding posts 13 is connected to each section of this plate. When the plug 9 is inserted into 80 the socket 8 it may be locked in either of two positions. For the purpose of locking this plug in either position a key operated plunger 14 is provided which is operated by the detachable key 15. This plunger works 85 in a suitable slot cut in the face of the plate 2. When the plug 9 is in one position the plunger 14 may be operated to project into the groove 12, and the plug will thus be locked in the position shown in Figure 2 90 with the metal collar 10 out of contact with the plate 3 and the circuit through the wiring 14 will be broken. When the plug is fully inserted into the block the plunger 14 may be actuated to project into the 95 groove 11. When the plug is locked in this position the metal collar 10 will contact with both sections of the plate 13 and establish a complete circuit through the battery wires 14. The numerals 16, 16 designate the 100 wires leading to the magneto. The terminals of these wires are connected to the

metallic plates 17, 17 which are fastened to the insulating plates 6 and 7 and which are protected by a surrounding guard 18 formed of insulating material. These metallic 5 plates 17 are formed with the spaced tongues 19, 19. A metallic rod 20 is threaded into the inner end of the plug 9 and when said plug is fully inserted into the socket 8 this rod fits through an aligned opening in the 10 plates 6 and 7, and between the tongues 19, 19, as indicated in dotted lines in Figure 2, thus establishing a circuit through the wiring 16. When the plug is in withdrawn 15 position, as shown in Figure 2 the rod 20 is out of contact with the tongues 19, at the same time that the metallic sleeve 10 is out of contact with the sections of the plate 3 and the circuit through the wiring 16 is broken.

From the foregoing it is obvious that the plug 9 may be inserted into the switch block and locked in either of two positions. When in one position a circuit will be established through the battery wiring and the magneto 25 wiring and when in the other position said circuits will be broken. When these circuits are broken, short circuits and burn outs of the electric system will be impossible. The generator will also be protected from 30 burning out and the battery will be protected from running down due to faulty cut out switch or other short circuits or grounds. The vehicle will also be protected from fire arising from short circuits and it will be 35 impossible to start the car or use the horn or lights thus protecting the vehicle from theft or unauthorized use.

What I claim is:—

1. A safety switch including a sectional 40 block, one section of which is formed of two members spaced apart, the other sections of the block being formed of insulating material, said block being formed with a central socket, a switch plug adapted to be inserted into said socket, said plug being formed with a metallic section, electrical wiring connected with each of said members, said metallic section contacting with said members to complete an electric 45 circuit when said plug is inserted in one position in said socket and being out of contact with said members to break said circuit when said plug is in its other position in said socket, and means for locking said plug 50 in either of said positions.

2. A sectional switch block, one section of which is formed with two members spaced apart and formed of electrical conducting 55 material, the other sections of said block being formed of insulating material, said block having a central socket, a switch plug adapted to be inserted in either of two positions in said socket, said plug having a section of conducting material which when in one position is in contact with said mem-

bers completing a circuit through them, and when in the other position is out of contact with said members, thus breaking said circuit, metallic plates fastened to the block and insulated therefrom and formed with spaced contact tongues, guards on opposite sides of said tongues, a metallic rod carried by the plug and contacting with said tongues when the plug is in position to complete a circuit through said members, but being out of contact with said tongues when said plug is in its other position. 70 75

3. A sectional switch block, one section of which is formed with two members spaced apart and formed of electrical conducting material, the other sections of said block being formed of insulating material, said block having a central socket, a switch plug adapted to be inserted in either of two positions in said socket, said plug having a section of conducting material which when in one position is in contact with said members, completing a circuit through them, and when in the other position is out of contact with said members, thus breaking said circuit, metallic plates fastened to the block and insulated therefrom and formed with spaced contact tongues, guards on opposite sides of said tongues, a metallic rod carried by the plug and contacting with said tongues when the plug is in position to complete a circuit through said members, but being out of contact with said tongues when said plug is in its other position. 80 85 90

4. A sectional switch block, one section of which is formed with two members spaced apart and formed of electrical conducting material, the other sections of said block being formed of insulating material, said block having a central socket, a switch plug adapted to be inserted in either of two positions in said socket, said plug having a section of conducting material which when in one position is in contact with said members, completing a circuit through them, and when in the other position is out of contact with said members, thus breaking said circuit, spaced contact tongues fastened to the block and insulated therefrom, a metallic rod carried by the plug and contacting with said tongues, when the plug is in position to complete a circuit through said members, but being out of contact with said tongues when said plug is in its other position, electrical wiring connected with said members, and electrical wiring connected with said tongues. 100 105 110 115 120

5. A safety switch including a sectional block, one section of which is formed of members spaced apart, the other sections of the block being formed of insulating material, said block being formed with a socket, a switch plug adapted to be inserted into said socket, said plug being formed with a 125 130

metallic section, electrical wiring connected with each of said members, said metallic section contacting with said members to complete an electric circuit when said plug 5 is inserted in one position in said socket and being out of contact with said members to break said circuit when said plug is in its other position in said socket.

In testimony whereof I have signed my name to this specification in the presence of 10 two subscribing witnesses.
